UNITED STATES PATENT OFFICE.

YEIKICHI OHTSUKA, OF TOKYO, JAPAN.

LEAF OF VACUUM-FILTERS FOR CYANID PROCESS.

1,111,609.

Specification of Letters Patent.

Patented Sept. 22, 1914.

Application filed February 4, 1914. Serial No. 816,639.

To all whom it may concern:

Be it known that I, YEIKICHI OHTSUKA, a subject of the Emperor of Japan, and a resident of Tokyo, Japan, have invented a new and useful Improvement in Leaves of Vacuum-Filters for Cyanid Process, of which the following is a full, clear, and exact description.

This invention relates to the construction of leaves of vacuum filters which are used for the separation of a solution of precious metals from its slime, in the cyanid process. A U-shaped suction pipe is attached to the horizontal head beam of the leaf, and a core, which consists of vertical center rods and horizontal woven strips is arranged between them. The filter cloth, which covers the both sides of the core and suction pipe outwardly, is attached to the head beam, and pressed on the core by the bars. By connecting the suction pipe to the vacuum pump, the filtrated liquid is sucked out from the suction holes in the bottom part of suction pipe. In the leaves of this kind, heretofore, a cocoa or plain mat is used as a core, and the liquid is sucked out by the bottom suction pipe, so the sucking action is stronger in the lower part of the leaf, and its action decreases gradually toward the upper part, for the resistance for filtration gradually increases by the capillary action in interior of the mat. In this manner, the sucking power is greatly different in the upper and lower parts of the leaf, and the thickness of mud deposited on the leaf is not uniform. In the working, high vacuum for suction always is required, for the lower part is quickly covered by the thick mud, by which the resistance for filtration of liquid is increased, and the resistance for filtration in the upper part is still greater, which is the great defect of the ordinary leaf of this kind.

The object of this invention is to improve this defect by the new construction of the core above stated, in which the vertical center rods pass through from the bottom suction pipe to the head beam in the center of the leaf to form spaces along the rods for the passage of the liquid, so that the sucking action of the bottom suction pipe is distributed at once uniformly throughout the whole surface of the leaf, and the defective resistance for filtration of liquid is greatly decreased, by which the power of the pump also may be greatly saved.

In the accompanying drawings—Figure 1 is a sectional elevation of the filter tank with the leaves arranged in their position; Fig. 2 is an elevation of a leaf according to this invention, in which a part is shown broken away to show the internal construction; Fig. 3 is a sectional side elevation of the leaf taken through the line A—B of Fig. 2; Fig. 4 is an enlarged sectional view taken through the line C—D of Fig. 2; Fig. 5 is an enlarged sectional view taken through the line E—F in Fig. 2; Fig. 6 is a fragmentary horizontal sectional view of the leaf; and Fig. 7 is a fragmentary horizontal sectional view of the leaf in modified form.

In Fig. 1, 1 are the leaves suspended or hung down side by side from the rectangular filter tank sides 2 in a set, and 4 is the tank edge. A conduit 6, which is connected to the slime reservoir by any proper method, in the bottom of the tank, conducts the slime from the reservoir to the tank, and the slime enters the tank through the ports 7. The numeral 3 represents the bottom doors, which may be opened downward by the hinges 9 to flow out the mud, but they are usually kept in water tight engagement with the sides or closed by means of the screw bolts 8 or weights 10, and the whole apparatus is supported by the beams 5 and pillars upon which the beams rest. These arrangements and constructions, however, may be conveniently designed and constructed.

In Figs. 2 to 6, inclusive, is shown the construction of a leaf according to this invention. A U-shaped suction pipe 16 is attached to a horizontal head beam 11 of the leaf, and suction holes or perforations 17 are provided only in the upper side of the bottom part of suction pipe. One end of the suction pipe is closed, and other end, which projects out above the head beam, is connected to a vacuum pump by any suitable method, so that the filtrated liquid shall be sucked out through the suction holes 17, in the operation of the pump. The projecting ends 12 of the head beam serve as hanging necks, while the leaf is suspended in the tank. Many vertical center rods 18, which preferably are made from bamboo sticks, are fastened vertically between the head beam 11 and the bottom part of suction pipe 16, these rods being properly spaced apart or distanced from each other. The two sheets 19^a, 19^b of horizontal strips, which preferably are

also made from bamboo and woven together by the strings 23, are fixed on both sides of the vertical center rods, and these form the core of the leaf. As the filter cloth 20, which 5 covers the core and the suction pipe outwardly, canvas or any other coarse woven materials shall be used in single or double, and it is pressed on the core by the bars 21 and bolts 22, connecting the same. The upper margin of the cloth is attached to the sides of head beam by the groove 13, in which the margin is grasped by bars 14 seated in the grooves and bolts 15, engaged through the bars and beam, as shown in 10 Fig. 4.

Fig. 7 shows the modification of the core, in which the horizontal strips are woven in alternately between the vertical center rods, instead of being woven together to form a 15 sheet by strings, as in the previous description.

According to the construction above stated, the vertical center rods 18 form the spaces 24 for the passage of liquid between 20 them in the center of the core, as shown in Fig. 6, and the spaces pass through from the bottom suction pipe to the head beam. In the modification, shown in Fig. 7, the spaces 25 24 are also formed in the center of the leaf 30 by the vertical center rods. When the vacuum pump is put into operation and the suction pipe 16 begins to absorb the filtrated liquid, the sucking action shall be spread over from the bottom to the top through the 35 spaces 24, and uniformly distributed throughout the whole surface of the leaf; so that the mud shall be uniformly deposited on the leaf, and the resistance for filtration is uniform in all parts of the leaf. On this 40 account, the working always can be operated in low vacuum, thus exceedingly saving the working power of the pump.

In the practical working of this invention,

the vertical center rods and horizontal strips of the core shall be made from bamboo 45 sticks, for the reason that they are light in weight, easily flexible and durable in use, but the other materials such as proper hard wood or metal rods may be conveniently used for the purpose. 50

Having thus fully described my invention, what I claim, and desire to secure by Letters Patent of the United States, is—

1. A leaf of vacuum filters having a core, consisting of vertical center rods of bamboo 55 and horizontal strips so disposed as to form clear vertical spaces for passage of filtrated liquid in the center of the leaf, substantially as and for the purpose hereinbefore described. 60

2. A leaf of vacuum filters comprising a supporting part, a U-shaped suction pipe attached to said supporting part, and a core, said core comprising spaced vertical center rods and horizontal strips on each side 65 thereof forming perforate mats and producing vertical spaces with the rods for the passage of filtrated liquid in the center of the leaf, filter cloths outwardly of the strips on both sides of the core and suction pipe, 70 and means carried by the supporting part outwardly of the cloths for holding the cloths against the strips and connecting said parts, said suction pipe having imperforate sides and apertures in the upper side of its 75 bottom portion communicating with the spaces whereby the suction resistance and deposit throughout the area of the core is rendered uniform.

In testimony whereof I have signed my 80 name to this specification in the presence of two subscribing witnesses.

YÉIKICHI OHTSUKA.
